UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,136,534.

Specification of Letters Patent. Patented Apr. 20, 1915.

Application filed September 10, 1913. Serial No. 738,028.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices 15 are released from a magazine in the order in which their characters are to appear in print and then assembled in line, the composed line transferred to the face of a mold, the mold filled with molten metal to form a slug 20 or linotype against the matrices which produce the type characters thereon, and the matrices thereafter returned through distributing mechanism to the magazine from which they started. More particularly, it 25 relates to such machines when equipped with a plurality of fonts of matrices, any one of which may be brought into action at will, and is designed to supplement the selected font by another capable of simultaneous employment therewith. Preferably and more 30 specifically, the supplemental font is contained in a magazine arranged in constant operative relation to the assembling devices, and the interchangeable fonts in a plurality 35 of magazines, any one of which may be brought into operative relation to the assembling devices, when desired. Further, it includes improvements in the form and mounting of the supplemental magazine to 40 facilitate its interchangeability. These and other features will be described in the specification and finally pointed out in the claims.

45 In the accompanying drawings, I have shown my invention as adapted to the commercial "Model 8" linotype, substantially as presented in the application for Letters Patent of John R. Rogers, Serial No. 624,426, filed May 1, 1911, wherein the magazines are movable with reference to the 50 assembling mechanism; but it will be understood that it is also applicable to machines like the commercial "Model 9" linotype, wherein the magazines are stationary and a portion of the assembling devices is shifted. 55 Further, it will be obvious that many

changes and variations may be made in the form and adaptation of my invention, which will still be comprised within its spirit. Thus, it may similarly be applied to other forms of typographical machines, such as 60 typesetters, typecasters and the like, which handle types or dies, instead of matrices.

Generally speaking, I desire it to be understood that I do not limit myself to any specific form or embodiment, except in so 65 far as such limitations are specified in the claims.

Referring to the drawings: Figure 1 is a side view of a portion of a linotype machine having my invention applied thereto; Fig. 70 2 is a front view thereof; Fig. 3 is an enlarged perspective view of the supplemental magazine, etc.; Fig. 4 illustrates an alternative construction of supplemental magazine; Fig. 5 is a section taken substantially 75 on the line 5—5 of Fig. 2; and Fig. 6 is a section taken substantially on the line 6—6 of Fig. 5.

As in the Model 8 linotype, or as presented in the previously-mentioned application, a 80 plurality of shiftable magazines A is so mounted and arranged that by the operation of the handle A¹, any selected one thereof may be brought into relation to the assembling 85 devices. The matrices are released from the active magazine by the manipulation of the keyboard A², and pass onto the belt B, whereby in turn they are delivered into the assembler B¹. The parts so far described, and except as hereinafter specified, 90 may be of any approved construction and mode of operation, and in themselves constitute no part of the present invention.

Arranged at the side of the magazines A 95 is an auxiliary or supplemental magazine C, wherefrom the matrices X are released by the manipulation of the keyboard C², and pass onto the before-mentioned belt B, it being observed that the latter is extended 100 so as to receive matrices from both the active magazine A and the supplemental magazine C, which are thus rendered simultaneously operative. The matrices X are returned to the active magazine A in the usual manner by distributing mechanism D, which is extended longitudinally (see Fig. 2) so as also to deliver the supplemental matrices to the magazine entrance D¹ and thence to the supplemental magazine C. It will be noted that due to the previously-described construction, 110

and mounting of the parts, I am enabled to select two magazines and bring them into operation simultaneously, so that matrices may be released from both and assembled 5 in the same line, as distinguished from the arrangement embodied in the Model 8 and Model 9 linotypes, wherein only one of the plurality of magazines is in action at a time.

It frequently happens in practice that the 10 auxiliary or supplemental magazine is used for matrices with large characters thereon, as for heads, advertising and the like, and that a small number of such matrices, say not more than ten to a channel, is sufficient 15 for the purposes. This quantity of matrices occupies only a comparatively small portion of the length of the magazine, and consequently the upper part thereof is useful only as a guide to the lower part. I have 20 therefore designed the special or sectional form of interchangeable magazine C, best shown in Figs. 2 and 3. In connection therewith I employ the upper or guiding section C¹, which remains permanently on the magazine and receives the matrices from the channel entrance D¹ and delivers them to the section C. The short and light interchangeable magazine C is easily and quickly handled, and so cheap to manufacture that 25 it is practicable to have a number of them always ready for use, and to act as a place of storage for the matrices when not in use, thus avoiding the inconvenience and loss of time involved in running matrices of one 30 font out of the magazine and replacing them with others. If for any reason it be desired to employ a larger quantity of supplemental matrices, this may be readily effected by the use of the full-length magazine F, as shown 35 in Fig. 4, which takes the place of both the short magazine C and the upper guiding section C¹.

The magazine section C and guiding section C¹ are both mounted on the magazine 40 frame E, the section C¹ being formed with depending lugs C²¹ adapted to engage in notches E²¹ in the frame and being held in position by the hooks E¹ pivoted on the frame, and the magazine C being similarly 45 held in position by the hooks E² pivoted on the frame. It will be noted that the cross-bars F¹ on the magazine F are of greater width than that of the notches E²¹ in the magazine frame, so that when the magazine 50 F is mounted thereon the bars will not enter the notches but will rest on top of the frame.

The section C¹ and magazine C are formed with the registering grooves C¹⁰ and C¹¹, 55 which are practically continuous and engage and guide the ears of the matrices (see Figs. 5 and 6). In order to secure the exact registration of the magazine C and section C¹, the latter is formed with the ledge or extension C²⁰ (see Figs. 3 and 5) projecting

from its lower edge, and on which the magazine C rests when in operative position.

As previously stated, I have shown my invention only in preferred form and by way of example, and as applied to the specific kind of machine indicated. Obviously, many modifications and alterations therein, and in its mode of application, will suggest themselves to those skilled in the art, without departure from its scope. 75

Having thus described my invention, its construction and mode of operation, what I claim and desire to secure by Letters Patent of the United States, is as follows:

1. In a typographical machine, the combination of distributing mechanism, and two sets of magazines arranged side by side in the machine, one of said sets comprising a plurality of magazines and movable independently of the other set to bring one or 80 another of its magazines into operative relation to the distributing mechanism. 85

2. In a typographical machine, the combination of assembling mechanism, and two sets of magazines arranged side by side in the machine, one of said sets comprising a plurality of magazines and movable independently of the other set to bring one or another of its magazines into operative relation to the assembling mechanism. 95

3. In a typographical machine, the combination of distributing mechanism, a plurality of magazines shiftable to bring one or another thereof into operative relation to the distributing mechanism, and a fixed magazine having a series of matrix channels and arranged at the side of said plurality with its channels in constant operative relation to the distributing mechanism; whereby different pairs of magazines may be brought 100 into use. 105

4. In a typographical machine, the combination of assembling mechanism, a plurality of magazines shiftable to bring one or another thereof into operative relation to the assembling mechanism, and a fixed magazine arranged at the side of said plurality and in constant operative relation to the assembling mechanism; whereby the different pairs of magazines may be brought into use. 110 115

5. In a typographical machine, the combination of distributing mechanism, and two sets of magazines arranged side by side in the machine, one of said sets comprising a plurality of magazines, and the other set a single magazine having a series of matrix channels and arranged with its channels in constant operative relation to the distributing mechanism, and means whereby the distributing mechanism may be connected to one or another of the magazines of the first set at will. 120

6. In a typographical machine, the combination of assembling mechanism, and two sets of magazines arranged side by side in 125 130

the machine, one of said sets comprising a plurality of magazines, and the other set a single magazine arranged in operative relation to the assembling mechanism, and 5 means whereby the assembling mechanism may be connected to one or another of the magazines of the first set at will.

7. In a typographical machine, the combination of distributing mechanism, a plurality of magazines, any selected one of which may be brought into operative relation to the distributing mechanism, a keyboard mechanism adapted to be connected to the selected magazine, a further magazine 15 having a series of matrix channels and arranged with its channels in operative relation to the distributing mechanism, and a separate keyboard mechanism for the further magazine; whereby different pairs of 20 magazines are adapted for simultaneous use.

8. In a typographical machine, the combination of three or more magazines, two keyboard mechanisms, and means whereby said keyboard mechanisms may be connected 25 to different pairs of said magazines to adapt them for simultaneous use.

9. In a typographical machine, the combination of a plurality of sets of magazines arranged side by side in the machine, and 30 means for moving one of said sets independently of the other to effect a change from one magazine to another therein; whereby different pairs of magazines may be brought into use.

35 10. In a typographical machine, the combination of a plurality of sets of magazines arranged side by side in the machine, a magazine of one set being arranged in position for conjoint use with one of another 40 set, and said other set being movable independently relatively to the first to bring different pairs of magazines into position for such conjoint use.

11. In a typographical machine, the combination of two sets of magazines, and distributing mechanism common to both sets, one of said sets comprising a plurality of 45 magazines and movable independently of the other set to bring one or another of its 50 magazines into operative relation to the distributing mechanism.

12. In a typographical machine, the combination of magazines each having a series

of matrix channels, and divided into two sets, a distributing mechanism common to both sets, one of said sets comprising a plurality of magazines, and means whereby one or another of the magazines of said set may be connected to the distributing mechanism, a magazine of the other set being arranged 60 so that its channels will maintain their connection with the distributing mechanism during the operation of said means.

13. In a typographical machine, the combination of a channeled magazine entrance, 65 a correspondingly channeled magazine remote therefrom, and an intermediate conductor to connect said parts and having a series of channels registering with those 70 therein.

14. In a typographical machine, the combination of a channeled magazine entrance adapted to coöperate with magazines of different length, and a correspondingly channeled conductor adapted to be used in conjunction with shorter magazines to connect 75 them with the said entrance.

15. In a typographical machine, the combination of a magazine entrance, a magazine of less than normal length, and an intermediate 80 conductor to connect said parts, said magazine and conductor both being removable to permit the substitution of a magazine of full length.

16. In a typographical machine, the combination of a channeled magazine entrance, a correspondingly channeled magazine of less than normal length, and an intermediate conductor to connect said parts and having 85 a series of channels registering with those 90 therein, the said magazine being removable so as to be interchangeable at will.

17. In a typographical machine, the combination of a magazine entrance, a magazine of less than normal length formed with 95 grooves to receive the type or matrices, and an intermediate conductor to connect said parts and formed with corresponding grooves to align with those in the magazine.

In testimony whereof I have affixed my 100 signature in presence of two witnesses.

DAVID S. KENNEDY.
